UNITED STATES PATENT OFFICE.

JOHN H. CORNELISON, OF ST. LOUIS, MISSOURI.

SWINGING SCREEN.

No. 864,886.

Specification of Letters Patent.

Patented Sept. 3, 1907.

Application filed September 25, 1906. Serial No. 336,154.

To all whom it may concern:

Be it known that I, JOHN H. CORNELISON, a citizen of the United States, residing at St. Louis and State of Missouri, have invented certain new and useful 5 Improvements in Swinging Screens; and I do hereby declare the following to be a full, clear, and exact description of the invention, such as will enable others skilled in the art to which it appertains to make and use the same, reference being had to the 10 accompanying drawings, and to the letters and figures of reference marked thereon, which form a part of this specification.

This invention relates to new and useful improvements in swinging screens for windows, doors, etc., and 15 the object of the invention is to produce a simple and efficient device of this nature comprising a hanger adapted to be pivotally mounted or fixed to the parting strip of a window frame, and so arranged that a screen may be conveniently hung thereon or detached from 20 the hanger.

More specifically the invention comprises a swinging screen provided with a hanger which is either fixed or pivoted to the guide strip of a window frame and adapted to engage a recess formed in a lateral projection 25 of the screen frame, the hanger being preferably bent so as to extend the width of the guide strip and projecting at right angles from the latter adjacent to one edge thereof, the pivotal screen connection between the hanger and screen frame being preferably below the 30 upper edge of the latter.

My invention comprises various details of construction and combinations and arrangements of parts which will be hereinafter fully described and then specifically defined in the appended claims.

35 I illustrate my invention in the accompanying drawings, which, with the letters of reference marked thereon, form a part of this application, and in which:—

Figure 1 is a perspective view of an integral swinging detachable hanger, showing the lateral projection there- 40 of substantially in the plane of the face of the guide strip of a window frame. Fig. 2 is a vertical sectional view through a screen frame and hanger engaging strip fastened thereto, showing in elevation the guide strip to which the hanger is pivoted. Fig. 3 is a slight modi- 45 fication of the hanger in which the same is mounted upon a pivot carried by the guide strip. Fig. 4 is a detail view of the hanger shown as fixed and attached to the guide strip, with its portion which pivotally engages the screen substantially in line with the face of 50 the guide strip. Fig. 5 is a sectional view through a guide strip, showing in top plan view the form illustrated in Fig. 4. Fig. 6 is a modified form of the construction disclosed by Figs. 4 and 5. Fig. 7 is a cross sectional view through a screen, showing the manner in 55 which the form of hanger disclosed in Fig. 1 is mounted.

Fig. 8 is a sectional view showing the manner of cutting away the upper rear corner of the screen frame to allow the same to swing when used in connection with a stationary hanger. Fig. 9 is a side elevation of the form shown in Fig. 8, and Fig. 10 is a perspective view 60 of a screen showing the recessed strip adapted to be fastened to the screen frame and to be engaged by the hanger.

Reference now being had to the details of the drawings by letter, A designates a hanger made preferably of 65 a piece of wire, B is a guide strip, and C designates the frame of a window. In the form shown in Fig. 1 of the drawings, the guide strip and frame are provided with registering holes A' to receive one end of the hanger which has pivotal connection therewith, and said 70 hanger is bent or curved at a point *a* substantially at a right angle and again at *a'*, having its lower end A² disposed substantially at right angles to the length of the guide strip and frame, and in line with one face of said strip, while the angled portion *a* is in line with the opposite face of the guide strip, these features of having the two angled portions adjacent to the opposite faces of the guide strip, obtaining through the various forms of my invention, and so designed for the purpose of filling the space which would intervene between the strip D 80 and the guide strips, one on either side of the window.

E designates the upper cross-piece of a screen frame to which the strip D is fastened in any suitable manner, a detail of said strip being shown clearly in Fig. 10 of the drawings. It will be noted that said strip is substantially 85 the length of the top E of the screen, stopping short of the longitudinal edges of the screen, and is provided with recesses D' formed in the under surface of said strip adjacent to its ends for the reception of the lower pivotal ends of the hangers. The upper portion 90 of said strip is preferably rounding, as shown clearly in Fig. 10 of the drawings, in order that the screen may turn freely without any interference of the strip with the sash of the window.

In Fig. 3 of the drawings, I have shown a screw or pin 95 F which is adapted to be fastened to the guide strip and upon which the form of hanger disclosed in Fig. 3 and designated by letter H, is pivotally mounted, said hanger H having an eye H' mounted upon the screw or pin. Otherwise, the hanger is of a similar construction 100 and arrangement as disclosed by Fig. 1 of the drawings.

Referring to Figs. 4 and 6 of the drawings, will be seen slight modifications of my invention, in which the hanger O is fixed or stationary, being fastened at one end to the guide strip being bent at an angle O', and 105 having its end O² for the reception of the recessed strip attached to the screen upon which the latter is pivotally mounted.

In Fig. 3 it will be noted that the hanger is bent at right angles and in Fig. 6 at an obtuse angle, a portion 110

of the hanger being driven diagonally through the guide strip and into the window frame, but in each case it will be noted that the portion of the hanger upon which the screen swings is substantially in line with one face of the 5 guide strip. In the forms of screens used upon stationary hangers, the corner of the upper strip of the screen that is supported by the hanger is cut away diagonally or rounded, as at R, so that the corner of the strip will not interfere with the sash when the screen is swung 10 away from the window frame.

From the foregoing, it will be noted that by the provision of a hanger for screens made in accordance with my invention, a simple and efficient device is provided which will be hidden from view and affording a simple 15 and efficient means whereby a screen may be easily hung or removed for storage or other purposes, and as the hanger is separate from the screen, the same is not liable to be broken in handling as is commonly the fault with the ordinary screens having projecting pivotal 20 points. In hanging the screen, the latter is simply raised a short distance above the hanger which has been mounted in the guide strip, and lowered so that the outer ends of the hanger will engage the recesses in the strip D.

25 What I claim is:—

1. In combination with the sash of a window and a guide strip upon the frame, a swinging screen frame, a recessed strip projecting from one face thereof, a hanger mounted upon the guide strip and extending the width of 30 the latter and engaging the recess of said strip, a space intervening between the end of said recessed strip and the outer edge of the upright portion of the screen and in which said hanger is positioned, as set forth.

2. In combination with the sash of a window and a 35 guide strip upon the frame, a swinging screen frame, a recessed strip projecting from one face thereof, a hanger mounted upon the guide strip and extending the width of the latter and engaging the recess of said strip, said hanger being bent at angles at two locations and extending the 40 width of the guide strip, with the portion between its an-

gles positioned intermediate the end of the recessed strip and the guide strip, as set forth.

3. In combination with the sash of a window and guide strip upon the frame, a hanger pivotally connected to the guide strip and bent to extend the width of the guide strip 45 with a pivotal end projecting at right angles from the latter, a screen frame, laterally projecting recessed strip upon said screen frame, recesses in the under edge of said strip and opening through the ends thereof, the pivotal ends of said hanger engaging said recesses, the portion of 50 the hanger which extends the width of the guide strip filling the space intermediate the end of the recessed strip and the guide strip, as set forth.

4. In combination with the sash and frame of a window, a guide strip upon said frame, a screen frame having 55 a recessed strip fastened upon the inner face thereof adjacent to the top of said screen frame, there being spaces between said guide and recessed strips, a pin or hanger fixed to the guide strip and having pivotal connection with the ends of said recessed strip below the upper end 60 of the screen frame, as set forth.

5. In combination with the sash and frame of a window, a guide strip upon said frame, a screen frame having a recessed strip fastened upon the inner face thereof adjacent to the top of said screen frame, there being spaces 65 between said guide and recessed strips, a pin or hanger fixed to the face of the guide strip at the outer edge thereof and having pivotal connection with the ends of said recessed strip below the upper end of the screen frame.

6. In combination with the sash and frame of a window, a guide strip upon said frame, a screen frame having a recessed strip fastened upon the inner face thereof adjacent to the top of said screen frame, there being spaces 75 between said guide and recessed strips, a hanger fixed to the guide strip and bent to extend the width of the guide strip and having its pivotal end extending horizontally and engaging the recesses of said strip below the upper marginal edge of the screen frame, as set forth.

In testimony whereof I hereunto affix my signature in 80 the presence of two witnesses.

JOHN H. CORNELISON.
